(57) **CLAIM**

The ornamental design for a docking station, as shown and described.

DESCRIPTION

FIG. 1 is a top perspective view of a first embodiment of an ornamental design for a docking station;
FIG. 2 is a bottom perspective view of the first embodiment thereof;

FIG. 3 is a top view of the first embodiment thereof;
FIG. 4 is a bottom view of the first embodiment thereof;
FIG. 5 is a first side view of the first embodiment thereof;
FIG. 6 is a second side view of the first embodiment thereof;
FIG. 7 is a front view of the first embodiment thereof; and
FIG. 8 is a rear view of the first embodiment thereof.

FIG. 9 is a top perspective view of a second embodiment of an ornamental design for a docking station;
FIG. 10 is a bottom perspective view of the second embodiment thereof;
FIG. 11 is a top view of the second embodiment thereof;
FIG. 12 is a bottom view of the second embodiment thereof;
FIG. 13 is a first side view of the second embodiment thereof;
FIG. 14 is a second side view of the second embodiment thereof;
FIG. 15 is a front view of the second embodiment thereof; and,

FIG. 16 is a rear view of the second embodiment thereof.
The broken lines immediately adjacent to the claimed surfaces represent boundaries of the claim in the embodiment in which they are shown. All other broken lines depict unclaimed environment. The broken lines and unshaded regions bounded by broken lines form no part of the claimed design.
